UNITED STATES PATENT OFFICE

JOSEPH MAY, OF FRANKFORT-ON-THE-MAIN, GERMANY

ARCH SUPPORT FOR FOOTWEAR

Application filed November 12, 1928, Serial No. 318,659, and in France October 6, 1928.

The present invention relates to arch support for footwear, consisting of two or more superposed blade springs of different length for supporting the arch of the foot. The 5 longest of these springs is at the bottom and the shortest at the top so that the ends of each of the shorter springs will bear on the top of the next longest spring arranged underneath, and thus have space for free move-
10 ment.

The separate springs are all of different curvature the shorter springs having a greater curvature than the springs underneath. At the centre of the curvature they 15 are connected together and firmly pressed together.

The connection may be effected by riveting, by a detachable screw connection or even by spot welding. The separate blade 20 springs may rest directly one upon the other at their point of connection. At this point there may, however be also provided very thin layers of another material such as rubber, either hard or soft, or vulcanized fibre.

25 It is essential, according to the invention, that the connection of the separate blade springs is only at the point of arching, and that only the lowermost spring will bear at its ends on the sole of the footwear, whilst 30 the next shorter spring bears on the back of the first spring, the next spring on the back of the second spring and so on. Any suitable number of separate blade springs may be arranged one upon the other according 35 to the supporting power adapted to be imparted to the complete structure. It will be understood that the arch support may also consist of only two superposed springs. The separate spring blades need not have the same general outline. Thus, for example, 40 the lowermost spring may be shaped in the form of a sole extending to the region of the ball of the foot whilst the uppermost spring may be semi-circular. The springs located 45 between the lowermost and the uppermost spring need not be formed in one piece but, for the purpose of increasing the elasticity, may be longitudinally divided, therefore consisting of two narrower springs which are 50 gripped or clamped between the lowermost

spring and the uppermost spring and thus firmly held in position by these. For increasing the elasticity the lowermost blade spring may be provided with one or more longitudinal slots which do not extend entirely 55 up to the ends of the spring. In forms of construction of the character last described the uppermost blade spring bridges over both the intermediate spaces between the middle narrow blade spring and the longitudinal slot in the lowermost blade spring, and is directly connected to the latter so that the intermediate spring layers are drawn together thereby. When the connecting means between the upper and lower spring are 60 passed through a longitudinal slot in the lower spring, the separate spring layers may also be moved relatively. For this purpose it will be understood that the upper spring blade may also be provided with longitudinal 65 slots.

The new arch support for footwear enables thin, very elastic and light separate springs to be used, which may also be made of light metals, and whilst having a high degree of 70 elasticity and greater lightness has a very high supporting capacity and rigidity.

The spring itself or the case which receives it may also be provided at the points under consideration with separate supporting and balancing means such as pads, wedges and the like. When of narrow shape and without a leather cover or case the new arch support can also be used as a so-called spring hinge 75 for insertion between the tread and inner sole at the shoe joint.

In the accompanying drawing is illustrated two examples of construction of the subject of the invention in the form of arch supports adapted to be loosely fitted into 80 footwear.

In accordance with the form of construction shown in Figures 1 to 3 the arch support consists of three separate blade springs, each made of one piece, of different sizes but having substantially the same outline, which are 85 connected together by a screw connection, whilst the construction shown in Figures 4 to 5 consists of three differently shaped 90 springs of which the middle one is formed 95 100

of two narrow springs and the separate springs are secured together by riveting.

Figure 1 is a longitudinal section through the separate superposed blade springs, which are still in the unstrained condition, on the line A—B of Figure 3.

Figure 2 is a longitudinal section of the spring insertion ready for use on the line A—B of Figure 3, and

10 Figure 3 is a plan of Figure 2,

Figure 4 is a longitudinal section, and

Figure 5 is a plan of an arch support ready for use according to the second form of construction.

15 In Figures 1 to 3, a , a^1 , a^2 , indicate the separate blade springs of different curvature which are firmly pressed together or against one another by means of a screw b secured to the underside of the uppermost spring

20 blade a^2 at the middle of the curvature thereof and passing through holes c in the other spring blades and adapted to be engaged by a nut d . On the nut d is fitted a pad e of elastic material, for example rubber, which

25 when the arch support is flattened bears against the sole of the footwear and thus prevents further flattening of the arch support. In cases where the separate spring blades are connected together at the point of

30 arching by rivets, spot welding or the like a pad for limiting the movement can be fitted in the curvature of the lowermost spring blade preferably on to pins or the like provided for the purpose. If the arch

35 support is to be enclosed in a case of leather or the like the pads for limiting the amount of flattening can be provided on the case, instead of on the spring, the case also being provided with other auxiliary means as for example supporting and position balancing pads or the like.

40 In Figures 4 and 5, f indicates the lowermost blade spring which is of the shape of an insole extending up to the region of the ball and is provided with a longitudinal slot g by which deleterious stresses when loading the spring are eliminated. To the lowermost spring f are riveted at i , i^1 two narrow blade springs h , h^1 and to these springs h , h^1 there is secured at l to the lowermost spring f a semi-circular plate k also of resilient material.

45 Also this form of construction may be provided with resilient pads for limiting the flattening of the lowermost spring and with a leather sole or it may be fitted into a case as described in connection with Figures 1 to 3.

50 I claim as my invention:

60 An arch support for footwear consisting of a lower longer blade spring provided with a longitudinal slot, an upper shorter blade spring, and two narrow intermediate blade springs located in spaced relation on said

65 lower blade spring and beneath said upper

blade spring and being connected to the latter, the upper blade spring bridging both the space between the intermediate blade springs and the slot in the lower blade spring and being connected directly to the lower blade spring so that the intermediate blade springs are drawn and held together by the upper spring and the lower spring.

70 In testimony whereof I affixed my signature.

JOSEPH MAY.
